PROTECTIVE SYSTEM

George D. Hanchett, Jr., Millburn, N. J., assignor
to Radio Corporation of America, a corporation
of Delaware

Application March 16, 1946, Serial No. 654,862

7 Claims. (Cl. 315—276)

1

This invention relates to protective systems such as are useful in producing an effect in response either to a relatively low impedance or to a relatively high impedance between a pair of conductors which may be, for example, the two rails of a railway crossover or the like.

It is well known that there exists between the rails of any section of a railway an impedance which varies with the weather from a relatively low impedance in wet weather to a relatively high impedance in dry weather. Such variation in impedance is denoted herein as the "normal range of variation" in the impedance between the two rails or conductors. Any protective system associated with such conductors (1) should be insensitive to this normal range of variation in the impedance, and (2) should be sensitive to impedances outside this normal range. Thus, in the case of a short circuit between the two conductors when the impedance is below the normal range, the protective system should produce an effect such as the lighting of a red signal. Likewise, in the case of an open or faulty circuit, when the impedance is above the normal range, the protective system should produce the same effect.

In a copending application of Hubert H. Wittenberg, Serial No. 631,723, filed November 29, 1945, is disclosed such a protective system wherein (1) a unilateral impedance device such as a rectifier is connected between the conductors at one of their ends, (2) an alternating potential input means and a resistor are connected in series between the conductors at the other of their ends, (3) a pair of electron discharge devices in push-pull relationship each has applied to its anode and shield grid alternating potentials which are arranged to be of opposite polarity for ensuring its deenergization when the potential of its control grid decreases to a predetermined critical value, (4) alternating potential bias means are connected between the conductors or rails and the control grid circuits of the two electron discharge devices so that one of the devices is deenergized during the positive half cycle of its anode potential in response to an impedance lower than the normal range and the other of said devices is deenergized during the negative half cycle of its anode potential in response to an impedance higher than the normal range, and (5) the cathode heaters of the two devices are each connected in series with its shield or screen grid so that the electron emission of the device is interrupted in response to opening of the screen grid circuit.

2

The protective system of the present invention is an improvement on that of the aforesaid copending application and affords added protection against failure of the protective system due to (1) all open or short circuits in the electron discharge devices themselves, and (2) short or open circuits in the various circuit components such as the resistor, capacitors, the rectifier, the transformer windings, etc. While the achievement of these additional results involve certain modifications of the system disclosed by the aforesaid copending application, the two systems are basically the same and involve the same mode of operation.

15 Important objects of the present invention are the provision of an improved protective system of the type which operates to produce a danger signal in response to an abnormal impedance between two conductors, and the provision of a protective system which functions to produce such a danger signal in response to failure of any of its components.

The invention will be better understood from the following description considered in connection with the accompanying drawings and its scope is indicated by the appended claims.

25 Referring to the drawing, Fig. 1 is a wiring diagram of the improved protective system, and Fig. 2 is an explanatory diagram relating to the operation of the system as affected by short or open circuits of certain resistors R₃ and R₄.

30 This system includes a pair of conductors 10 and 11. Connected between these conductors at one of their ends is a unilateral impedance device such as a rectifier 12. At the other of their ends, the two conductors are interconnected through a resistor 13 and alternating current input means shown as the secondary winding 14 of a transformer.

40 A pair of electron discharge devices 15 and 16 connected in push-pull relationship have their various operating potentials applied from the transformer secondary windings 17, 18, 19 and 20 and have their control potentials applied from

45 the secondary winding 14 which is connected between the conductors 10 and 11 as previously indicated. The various pins or terminals of the device 15 are indicated by the reference numerals 1 to 7 and the corresponding terminals of the device 16 are indicated by the reference numerals 1' to 7'. The devices 15 and 16 are preferably of the gaseous conduction type sometimes designated by the term "Thyratron."

50 With respect to the device 15, it will be noted (1) that its cathode heater is connected across

the lower 6.3 volt half of the secondary 14, (2) that its output circuit includes the operating coil of a relay RL-1, the 150 volt secondary 17, the shield grid 21, an adjustable part of a resistor R₄ and the lower mid-section of the secondary 19, (3) that its shield grid potential is determined by the lower mid-section of the secondary 19 and the secondary 18, and (4) that its control grid potential is applied through a resistor R₅ from an 8 volt tap of the secondary 14. The operating coil of the relay RL-1 is shunted by a capacitor C₁ and a resistor R₁.

Similarly with respect to the device 16 it is seen (1) that its cathode heater is connected across the upper 6.3 volt half of the secondary 19, (2) that its output circuit includes the operating coil of a relay RL-2, the 150 volt secondary 20, the shield grid 22, an adjustable part of a resistor R₃ and the upper mid-section of the secondary 19, (3) that the potential of its shield grid 22 is determined by the upper mid-section of the secondary 19 and the secondary 18, and (4) that its control grid potential is applied through a resistor R₆ from the conductor 11. Connected in shunt to the operating coil of the relay RL-2 are a capacitor C₂ and a resistor R₂.

The relays RL-1 and RL-2 are series connected in a control circuit in a well known manner so that deenergization of either of them actuates a controlled device such as a danger signal.

So long as the impedance between the conductors 10 and 11 is within its normal range and there are no defects in the protective system, the devices 15 and 16 are energized due to the fact that their control grid potentials are more positive than the critical voltage at which they are deenergized. When the impedance between the conductors 10 and 11 is below its normal value and that the polarity is such that the conductor 11 is positive, (1) the voltage between the conductors 10 and 11 is reduced due to the increase in current through the resistor 13, and (2) the grid potential of the device 16 is reduced below its critical value so the device 16 is deenergized. When the polarity is such that the conductor 10 is positive and the combined series impedance of conductors 10 and 11 and the rectifier 12 is above its normal value (1) less current is drawn through the resistor 13, and (2) the grid potential of the device 15 is reduced below its critical value so that the device 15 is deenergized.

Deenergization of the electron discharge devices and relays is also produced by various kinds of defects in the protective system.

Considering first open circuits between the different terminals of the device 15, it is seen that the device 15 and the relay RL-1 are deenergized in response to an open circuit at (1) the terminal 1 which will remove the signal from the device 15 which is operated as a positive grid tube by the use of a negative voltage on the shield grid 21, (2) the terminal 2 which will interrupt the plate circuit of the device 15, (3) the terminal 3 or 4 which will interrupt the heater circuit, (4) the terminal 5 or 7 which will interrupt the plate circuit, or (5) the terminal 6 which will interrupt the plate circuit. The effects of open circuits on the device 16 are similar to those stated in connection with Fig. 2.

The device 15 and the relay RL-1 are deenergized in response to a short circuit between (1) the terminals 1 and 2, 3 or 4 which removes the control signal from the device 15 and places a reduced voltage on the grid while the anode is positive, (2) the terminals 1 and 5 or 7 which

places a negative voltage on the control grid while the anode is positive, (3) the terminals 1 and 6 which places sufficient alternating potential across the coil of relay RL-1 to open its circuit (R₅ must be low enough in value that enough alternating current is drawn through the relay coil RL-1 to deenergize it. The same is true of R₆), (4) the terminals 3 and 2 or 4 which interrupts the electron emission, (5) the terminals 6 and 2, 3 or 4 which places sufficient alternating potential across the coil of relay RL-1 to open it, (6) the terminals 6 and 5 or 7 which places sufficient alternating potential across the coil of relay RL-1 to open it, and (7) the terminals 5 or 7 and 2, 3 or 4 which reduces the shield voltage of the device 15 to zero.

In connection with the last item (7), it should be understood that a short circuit between the terminals 5 or 7 and 2, 3 or 4 short circuits the lower mid-section of the secondary 19 thus reducing the load on the secondary 18 so that the secondary 18 draws less current through the upper mid-section of the secondary 19 and the right hand section of the resistor R₃ thereby applying to the shield grid 22 of the device 16 a more negative voltage by which the device 16 and the relay RL-2 are deenergized. In like manner, the device 15 and the relay RL-1 are deenergized in response to a short circuit between the terminals 5' or 7' and 2', 3' or 4' of the device 16. What has been said of other defects of the device 15 is also true of the device 16.

With respect to short circuits or open circuits in the various components of the system, it is seen that either a short or open circuit in C₁ or R₁ will reduce the unidirectional voltage across the relay RL-1 to a value at which the relay RL-1 opens and that the relay RL-2 similarly opens in response to open or short circuits in C₂ or R₂.

With respect to the resistor R₃, a short circuit between its terminals A and B makes the shield grid 22 more negative thus deenergizing the device 15 and relay RL-1, an open circuit at the terminal A makes the shield grid 22 more negative thus deenergizing the device 15 and the relay RL-1, an open circuit at the terminal B makes the shield grid 22 more negative thus deenergizing the device 15 and relay RL-1 and an open circuit in the movable contact lead opens the anode circuit of the device 15 and deenergizes the relay RL-1. The effects of defects in the resistor R₄ are similar to those set forth in connection with the resistor R₃.

How these results are produced is evident from the following analysis of Fig. 2: Normal condition,

(a) 15 and 16 conduct on alternate half cycles with 15 conducting.

(b) Plate current in right half of R₄ balances voltages of 18 and 19.

(c) A short 1 to 2 upsets this balance so that current from 18 produces in right half of R₃ a more negative voltage which is applied to 1' deenergizes 16.

(d) Open at A' applies 151.2 v. between 2 and the anode of 15, plate current of 15 (smaller than normal) goes through R₃ and left half of R₄, 22 is more positive, 21 is much more positive, next half cycle makes 22 more negative and deenergizes 16.

(e) Open at B' applies 145.3 v. between 2 and anode of 15, grids 21 and 22 are more positive, next half cycle makes 22 more negative, and deenergizes 16.

An open circuit in the resistor R₅ or R₆ will

interrupt the control signal and deenergize the device 15 or 16 to which it is connected. A short circuit on either of these resistors will shorten the life of the device 15 or 16 to which it is connected but will not affect the operation of the protective system.

With respect to the resistor 13, (1) an open circuit will remove the voltage between the conductors 10 and 11 thus interrupting the control voltage of the device 16 and deenergizing the relay RL-2 and (2) a short circuit will decrease the signal on the device 15 and deenergize the relay RL-1.

If the rectifier 12 fails, the device 16 and the relay RL-2 are deenergized. If it is short circuited, the device 15 and the relay RL-1 are deenergized.

Short circuits across any of the windings of the power transformer will burn them out thus removing the voltage across the relay coils. A break in the winding 17 will open the relay circuits. A break in the winding 19 will interrupt the heater current of the device 15 or 16. A break in the winding 14 will remove voltage from the conductors 10-11 while a break in the 8-volt section of this winding will remove signal from the device 15. A break in the winding 18 will increase the negative shield voltage on both devices 15 and 16 thus deenergizing both devices and the corresponding relays.

Thus the outstanding characteristic of the improved protective system of the present invention is a circuit arrangement such that the failure of any part likely to affect the operation of the system immediately produces an indication of such failure.

I claim as my invention:

1. The combination of a series circuit including a pair of impedance devices each provided with a terminal intermediate its ends, bias voltage means connected between said impedance means at one of their ends and provided with a midpoint terminal, means connected between said impedance means at the other of their ends for applying a voltage which is opposed to said bias voltage and a value smaller than said bias voltage, and a pair of electron discharge devices having their cathodes connected to the midpoint terminal of said bias voltage means and their shield grids each connected to a different intermediate terminal of said impedance means.

2. The combination of a series circuit including a pair of impedance devices each provided with a terminal intermediate its ends, bias voltage means connected between said impedance means at one of their ends and provided with a midpoint terminal, means connected between said impedance means at the other of their ends for applying a voltage which is opposed to said bias voltage and a value smaller than said bias voltage, a pair of electron discharge devices having their cathodes connected to the midpoint terminal of said bias voltage means and their shield grids each connected to a different intermediate terminal of said impedance means, and means for simultaneously applying between the shield grids and anodes of said electron discharge devices plate voltages of opposite polarity.

3. The combination of a series circuit including a pair of resistors each provided with a terminal intermediate its ends, a bias voltage transformer winding connected between said resistors at one

of their ends and provided with a midpoint terminal, a transformer winding connected between said resistors at the other of their ends for applying a voltage which has a polarity opposed to that of said bias voltage winding and has a smaller value than said bias voltage, and a pair of electron discharge devices having their cathodes connected to midpoint terminal and their shield grids each connected to a different one of said intermediate terminals.

4. The combination of a series circuit including a pair of resistors each provided with a terminal intermediate its ends, a bias voltage transformer winding connected between said resistors at one of their ends and provided with a midpoint terminal, a transformer winding connected between said resistors at the other of their ends for applying a voltage which has a polarity opposed to that of said bias voltage winding and has a smaller value than said bias voltage, a pair of electron discharge devices having their cathodes connected to midpoint terminal and their shield grids each connected to a different one of said intermediate terminals, and a pair of oppositely polarized transformer windings each connected between the shield grid and anode of a different one of said electron discharge devices.

5. The combination of a series circuit including a pair of resistors each provided with a terminal intermediate its ends, a bias voltage transformer winding connected between said resistors at one of their ends and provided with a midpoint terminal, a transformer winding connected between said resistors at the other of their ends for applying a voltage which has a polarity opposed to that of said bias voltage winding and has a smaller value than said bias voltage, a pair of electron discharge devices having their cathodes connected to midpoint terminal and their shield grids each connected to a different one of said intermediate terminals, a pair of oppositely polarized transformer windings each connected between the shield grid and anode of a different one of said electron discharge devices, a pair of conductors between which there exists a normal range of impedance variation, and means for applying to the control grids of said electron discharge devices voltages whereby they are selectively deenergized in response to interconductor impedance values which are higher than said range and lower than said range.

6. The combination of an electron discharge device having an anode and a cathode and control and shield grids, a source of potential, and means connecting said anode to said cathode through said source and said shield grid.

7. The combination of an electron discharge device having an anode and a cathode and control and shield grids, a source of potential, a load device to be operated, and means connecting said anode to said cathode through said source, said shield grid and said load device.
